(57) **CLAIM**

The ornamental design for an in-vehicle amplifier, as shown and described.

DESCRIPTION

FIG. 1 is a perspective view from the front of an in-vehicle amplifier showing my new design;

FIG. 2 is a front view of the in-vehicle amplifier of FIG. 1; FIG. 3 is a rear view of the in-vehicle amplifier of FIG. 1 and FIG. 2;

FIG. 4 is a top view of the in-vehicle amplifier of FIG. 1 and FIG. 2;

FIG. 5 is a bottom view of the in-vehicle amplifier of FIG. 1 and FIG. 2;

FIG. 6 is a right side view of the in-vehicle amplifier of FIG. 1 and FIG. 2; and,

FIG. 7 is a left side view of the in-vehicle amplifier of FIG. 1 and FIG. 2.

The broken lines depict portions of the in-vehicle amplifier that form no part of the claimed design.

The unshaded surfaces immediately adjacent the broken lines shown in FIG. 3 form no part of the claimed design.
